SOOT BLOWER SEAL

Robert Hudson Wager, Maplewood, N. J.

Application May 13, 1938, Serial No. 207,852

9 Claims. (Cl. 285—30)

The invention relates to the devices for blowing soot from boiler tubes, of the general type having a rotatably or non-rotatably mounted blower element passing through an opening in the boiler wall, said blower element having jets for directing the soot-blowing air or steam in various directions against the boiler tubes and/or other internal parts of the boiler. Due to high temperatures and temperature changes, such a blower element is subject to severe expansion, contraction, and warping, making it very difficult to provide a constantly tight seal between the outer end of the blower element and the boiler wall to prevent soot from blowing out of the opening through which said blower element extends into the boiler furnace.

While relatively complicated and expensive seals heretofore devised for the above mentioned purpose, have possessed a fair degree of efficiency with relatively little maintenance trouble, seals of comparatively simple and inexpensive construction have fallen short of requirements as to efficiency, trouble-free operation and durability. It has been the object of the present invention, however, to provide a seal to meet all requirements and at the same time be of such simple and inexpensive construction as to be truly practicable, and actual manufacture, installation and use have shown that this end has been attained.

Fig. 1 of the accompanying drawings is a vertical longitudinal sectional view partly in elevation showing a preferred assemblage of parts for carrying out the invention.

Fig. 2 is a vertical transverse sectional view on line 2—2 of Fig. 1.

Fig. 3 is a detail section partly in elevation showing a thrust collar which may be used for the packing spring, if desired.

Fig. 4 is a fragmentary view similar to Fig. 1 but showing a modified construction.

Fig. 5 is a transverse sectional view substantially on line 5—5 of Fig. 4.

Fig. 6 is a horizontal sectional view on line 6—6 of Fig. 5.

Fig. 7 is an inner side elevation of the abutment ring for the spring, shown in Fig. 4.

Fig. 8 is a horizontal sectional view of the abutment ring on line 8—8 of Fig. 7.

Figs. 9 and 10 are detail sectional views illustrating anti-friction thrust bearings which may be provided for the spring.

While preferred features of construction have been shown and will be specifically described, attention is invited to the possibility of making

numerous variations within the scope of the invention as claimed.

In Fig. 1, a portion of a boiler wall 5 is shown including an outer hollow wall 6 and an inner wall or baffle plate 7, there being an air space 8 between said walls 6 and 7. An angle-metal or channel ring 9 is rigidly included in the wall 6, said ring having a substantially cylindrical flange 10 at its periphery and a second flange 11 which projects inwardly from the outer edge of said flange 10. A metal sleeve 12 extends between the two walls 6 and 7 and passes through the ring 9 in contact with the inner edge of the flange 11, the outer end of said sleeve being extended beyond said flange in the present showing. The inner end of the sleeve 12 is shown as contracted and welded at 13 to the inner wall or baffle plate 7, around an opening 14 in the latter.

In the space between the sleeve 12 and the cylindrical flange 10 of the ring 9, there is a fireproof packing 15 and a retaining ring 16 for said packing. A gasket 17 lies against this retaining ring and the thimble 12 is provided with an integral peripheral flange 18 lying against said gasket. Bolts 20 pass through the parts 18, 17, 16, 15 and 11, and project outwardly beyond the latter. Clamping nuts 21 are threaded on these bolts 20 in contact with washers 19, thereby holding the parts through which the bolts pass in rigid relation with the sleeve 12.

All of the above may be considered as conventional construction.

The outer ends of the bolts 20 project considerably beyond the projecting outer end of the sleeve 12 and pass through relatively large openings 22 in a vertical plate 23 (Figs. 1 and 2) which extend across the outer end of said sleeve 12. A gasket 24 is interposed between the plate 23 and the plate 12, washers 25 extend over the openings 22 at the outer side of the plate 23, and nuts 26 are threaded on the outer ends of the bolts 20 to force plate 23 toward the sleeve 12, thereby fluid-tightly clamping the gasket 24 in place and preventing any leakage of dust-laden gases. Leakage around the exterior of the sleeve 12 is prevented by the packing 15 and the gasket 17, and any possible leakage through the bolt holes and under the nuts 21 is prevented by said gasket 17 and the washers 19.

The plate 23 is formed with an opening 27 about concentric with the sleeve 12 but of considerably less diameter than said sleeve. The rotatable or non-rotatable blower element 28 extends from the usual blower head or the like 29

through the opening 27, through the sleeve 12 and through the opening 14 into the furnace of the boiler, said blower element being inwardly spaced from the edges of said openings 27 and 14 and being, therefore, also in inwardly spaced relation with said sleeve 12. One of the steam or air discharge jets of the blower element 28 is shown at 30 but I have not illustrated any means for rotating said blower element nor means for supplying steam or compressed air thereto, all of which are well known in the art.

A flexible metal sleeve 31 of circumferentially corrugated nature, is disposed within the rigid sleeve 12 and surrounds the blower element 28, being spaced from both said sleeve 12 and blower element 28. At its outer end, the sleeve 31 is welded or otherwise fluid-tightly secured to the plate 23 around the opening 27, the welding or the like being indicated at 32. The inner end 20 of the sleeve 31 is similarly welded or otherwise secured at 33 to a circular closure 34 which surrounds the blower element 28, said closure having a cylindrical wall portion 35 in spaced concentric relation with said blower element, and an inwardly projecting flange 36 at the edge of said wall toward the opening 14. Appropriate heat-resisting packing 37 is provided in the channeled seat formed by the closure portions 35 and 36 and the contiguous portion of the blower element 28, said packing contacting fluid-tightly with the periphery of said blower element. A follower ring 38 is shown contacting with the packing 37 and the inner end of a coiled compression spring 39 is shown abutting said follower ring to inwardly press the latter, thereby holding the packing 37 operatively seated to prevent any leakage of dust-laden gases into the sleeve 31. However, as will hereinafter appear, other spring means may be provided in place of spring 39, as in Figs. 4 and 9, hereinafter described, for example. When spring 39 is used, its outer end may directly abut a portion of the blower head or the like 29 as seen in Fig. 1 or a thrust shoulder may be provided in any other suitable way, for instance, by means of a collar 40 secured by a set screw 41 to the blower elements 28, as illustrated in Fig. 3, or in the ways illustrated in Figs. 4, 9 and 10, later described. When the spring directly abuts the blower head or the like 29, the latter is preferably provided with a shallow groove 42 forming a seat for the outermost convolution of said spring.

In Figs. 4 to 8, a modification is shown. In these views, the elements 12^a, 23^a, 24^a, 20^a, 25^a, 28^a, 35^a, 37^a, 28^a, and 31^a correspond to the elements 12, 23, 24, 20, 25, 26, 35, 37, 28 and 31 above described. The opening 27^a of the abutment plate 23^a, however, is provided with notches 23^b in its edge wall, and the inner side of said plate is provided with depressed seats 23^c circumferentially spaced from said notches. An abutment ring 39^a is provided for the spring 39^b which seats the packing 37^a, being provided with a rib 39^c to surround the outermost coil of said spring. Ring 39^a is provided with radial lugs 39^d and said ring is insertable through the opening 27^a when said lugs are alined with the notches 23^b. Then, the ring is turned until the lugs 39^d seat in the seats 23^c, in which they are held by the pressure of spring 39^b if desired and while its inner end may be associated with the packing 37^a in the same manner as spring 39^b is associated with packing 37. I prefer to interpose a sleeve 39^e between said spring 39^b and said packing 37^a.

In Fig. 9, a ball thrust bearing 48^a is provided, against which the packing-seat spring 39^e may thrust, and a packing-engaging sleeve 39^b is shown abutting the inner end of said spring. This arrangement may be used instead of those shown in Figs. 1 and 3 if desired.

In Fig. 10, I have shown another form of thrust bearing which may be used for the packing-seating spring. In this view, 40^b denotes a collar suitably secured on the blower element, 40^c refers to a steel washer against which the spring abuts, and 40^d has reference to a bronze washer between said collar 40^b and washer 40^c.

Obviously, the thrust bearings shown in Figs. 9 and 10 would be used only when the blower element be rotatable, but such arrangements as those shown in Figs. 1 and 4 also operate advantageously with a rotatable blower element, without the necessity of an anti-friction thrust bearing.

From the foregoing taken in connection with the accompanying drawing, it will be seen that comparatively simple and inexpensive construction has been provided for positively preventing any leakage of dust-laden gases out of the opening through which the blower element enters the furnace. Moreover, the seal will remain tight, no matter how much the blower element may expand and contract and no matter how much said blower element may become warped from the heat. Furthermore, the seal will give long trouble-free operation and will not be affected by any longitudinal lunging of the blower element which may occur during the performance of a soot-blowing operation. If the blower element be so warped that its outer end portion cannot rotate truly, the flexible metal sleeve will readily yield and allow the packing to remain in tight sealing contact with said blower element. In short, an effective seal is provided under all conditions encountered.

While excellent results have been obtained from the details shown and described, and they are therefore preferably followed, attention is again invited to the possibility of making variations within the scope of the invention as claimed.

I claim:

1. In a soot blower having a blower element extending through a relatively large opening in a boiler wall; a flexible metal sleeve surrounding said blower element within said opening, said flexible metal sleeve being spaced from the wall of said opening and from said blower element, a plate having an opening through which said blower element passes without contact with said plate, the front end of said flexible metal sleeve being fluid-tightly secured to said plate around said opening thereof, said plate being secured to the boiler wall and fluid-tightly closing the outer end of said wall opening around said flexible metal sleeve, means fluid-tightly closing the inner end of said flexible sleeve around said blower element and including a packing, spring means for seating said packing, and an abutment ring against which said spring means thrusts, said abutment ring surrounding said blower element and having peripheral lugs abuttings the inner side of said plate, the opening of said plate being notched to permit passage of said lugs when said abutment ring is sufficiently turned.

2. A structure as specified in claim 1; said inner side of said plate being provided with depressed seats normally receiving said lugs.

3. In a soot blower having a blower element

- extending through a relatively large opening in a boiler wall; a flexible metal sleeve in said opening, surrounding and spaced from said blower element, and extending toward the interior of the boiler, means for non-rotatably connecting the outer end of said flexible metal sleeve with the boiler wall and for fluid-tightly closing said opening around said outer end of said flexible metal sleeve, a circular closure for the inner end of said flexible metal sleeve constituting a packing seat, a packing surrounding said blower element within said sleeve and engaging said seat, and spring means within said sleeve and thrusting against said packing for holding the same operatively seated.
4. In a soot blower having a blower element extending through a relatively large opening in a boiler wall; a flexible metal sleeve in said opening, surrounding and spaced from said blower element, and extending toward the interior of the boiler, means for non-rotatably connecting the outer end of said flexible metal sleeve with the boiler wall and for fluid-tightly closing said opening around said outer end of said flexible metal sleeve, a circular closure for the inner end of said flexible metal sleeve, said closure having a cylindrical wall surrounding and spaced from said blower element and an annular flange projecting inwardly from the inner end of said cylindrical wall, providing a circular channeled seat which opens toward the outer end of said flexible metal sleeve, a circular packing in said seat and contacting with said blower element, and spring means surrounding said blower element within said flexible metal sleeve and thrusting against said packing to hold the same operatively seated.
5. In a soot blower having a blower element extending through a relative large opening in a boiler wall; a flexible metal sleeve in said opening, surrounding and spaced from said blower element, and extending toward the interior of the boiler, a plate having an opening through which said blower element passes without contacting said plate, the front end of said flexible metal sleeve being fluid-tightly secured to said plate around said opening thereof, said plate being secured to the boiler wall and fluid-tightly closing the outer end of said wall opening around said flexible metal plate, a circular closure for the inner end of said flexible metal sleeve and constituting a packing seat, a packing surrounding said blower element within said sleeve and engaging said seat, and spring means within said sleeve and thrusting against said packing for holding the same operatively seated.
6. In a soot blower having a blower element extending through a relatively large opening in a wall; means for preventing escape of soot through said opening around said blower element, including a flexible metal sleeve surrounding and spaced from said blower element and a packing in the inner end of said sleeve, spring means within said flexible sleeve for seating said packing, an abutment ring against which the outer end of said spring means thrusts, said abutment ring surrounding said blower element and being spaced therefrom, a fixed abutment adjacent said abutment ring and also surrounding and spaced from said blower element, and connecting means between said abutment ring and said fixed abutment releasable by turning of said ring with respect to said fixed abutment.
7. In a soot blower having a blower element extending through a relatively large opening in a wall; means for preventing escape of soot through said opening around said blower element, including a flexible metal sleeve surrounding and spaced from said blower element and a packing in the inner end of said sleeve, spring means within said flexible sleeve for seating said packing, an abutment ring against which the outer end of said spring means thrusts, said abutment ring surrounding said blower element and being spaced therefrom, a fixed abutment adjacent said abutment ring and also surrounding and spaced from said blower element, and lugs on said abutment ring abutting portions of said fixed abutment and releasable therefrom by turning of said abutment ring with respect to said fixed abutment.
8. In a soot blower having a blower element extending through a relative large opening in a wall; means for preventing escape of soot through said opening around said blower element including a flexible metal sleeve surrounding and spaced from said blower element and a packing in the inner end of said sleeve, spring means within said flexible sleeve for seating said packing, an abutment ring against which the outer end of said spring means thrusts, said abutment ring surrounding said blower element and being spaced therefrom, a fixed abutment at outer side of said abutment ring and surrounding said blower element, and peripheral lugs on said abutment ring lying against the inner side of said fixed abutment, said fixed abutment being spaced sufficiently from said blower element to allow outward passage of said abutment ring when said lugs are freed from said fixed abutment, the inner edge of the latter having notches through which said lugs may pass when said abutment ring is turned with respect to said fixed abutment.
9. A structure as specified in claim 8; the inner side of said fixed abutment being provided with depressed seats normally receiving said lugs of said abutment ring.

ROBERT HUDSON WAGER.
